(57) **CLAIM**

I claim the ornamental design for a pyramid sand mold, as shown and described.

DESCRIPTION

FIG. 1 is an exploded perspective view of a pyramid sand mold, showing my new design in a disassembled position; FIG. 2 is a perspective view thereof, illustrated in an assembled position;

FIG. 3 is a front elevational view of FIG. 2;

FIG. 4 is a rear elevational view of FIG. 2;

FIG. 5 is a left-side elevational view of FIG. 2;

FIG. 6 is a right-side elevational view of FIG. 2;

FIG. 7 is a top plan view of FIG. 2; and,

FIG. 8 is a bottom plan view of FIG. 2.

The stippled shading showing sand in FIG. 1 depicts environmental matter and forms no part of the claimed design.
